AUTOMATIC LOCK SLIDER

Davis Marinsky, Bronx, N. Y., assignor of one-half to Louis H. Morin, Bronx, N. Y.

Application October 8, 1943, Serial No. 505,450

12 Claims. (Cl. 24—205.5)

This invention relates to sliders for separable fastener stringers. More particularly, the invention relates to sliders for fasteners of the kind described employing means for automatically retaining the slider against movement on the stringers, the means being in the form of a pivoted lock element of substantial T-formation and including an extending spring finger, depressed by the finger piece or pull to move the cross head of the lock element into inoperative position in the operation of moving the slider along the stringers to uncouple or separate the stringers.

The novel features of the invention will be best understood from the following description when taken together with the accompanying drawing, in which certain embodiments of the invention are disclosed, and in which the separate parts are designated by suitable reference characters in each of the views; and in which:

Fig. 1 is a perspective view of a slider made according to my invention, showing the slider detached from the stringers.

Fig. 2 is a side and sectional view of the slider diagrammatically illustrating the same in locked position; and

Fig. 3 is a view similar to Fig. 2, showing the slider parts in the unlocked position.

The slider comprises top and bottom walls 10 and 11, spaced apart and coupled at the wide end of the slider by a connecting web 12, and the side edges of the walls 10 and 11 are provided with inturned flanges 13. Arranged centrally and longitudinally of the wall 10 is an elongated loop 14 for attachment of a pull of any type and kind, a part of which is indicated at 15 in the accompanying drawing.

The pull attaching loop at the narrow or contracted end of the slider body, and where it joins the wall 10, is provided with an aperture 16. At 11 is shown the lock element of the slider. This element is substantially of T-formation, and comprises a cross head 18 extending substantially the full width of the channel portion of the slider. On the lower surface of the cross head are laterally and longitudinally spaced projections 19 and 20, adapted to be positioned between adjacent scoops on both stringers, as is diagrammatically illustrated in Figs. 2 and 3 of the drawing, in which the scoops 21 are on one stringer, and the scoops 22 on the companion stringer.

Offset slightly from the other or top side of the cross head 18, is an extending leg or arm 23 of a lock element. This element is arranged in the aperture 16 of the loop 14, and is pivoted therein by a pivot pin 24. It will be apparent that the offsetting of the leg or arm 23 disposes

the upper surface of the cross head 18 substantially in alignment with the corresponding surface of the wall 10 so that the lock element forms more or less of an extension of this wall, and its outer edge 25 is preferably rounded, as clearly seen in Fig. 1.

The upper edge of the arm 23 is curved downwardly, as seen at 26, to form a neat and finished appearance at the contracted end of the slider. 10 The upper rear surface of the arm 23 is recessed to receive one end of a long spring arm or finger 27, which is secured in position by a screw or other fastening, as at 28, note Fig. 1. The spring finger 27 extends longitudinally and beneath the loop 14, and its inner end 29 normally rests upon the upper surface of the wall 10, so as to support the element 17 in the operative position shown in Fig. 2 of the drawing.

It will appear that the projections or pins 19, 20 have rounded corners, so that in moving the slider along the stringers to couple the same, that is to say, when moving in the direction of the arrow 30, Fig. 2, the lock element will ratchet over the scoops by reason of the light tensional engagement of the lock element with the scoops through the medium of the spring finger 27. However, in the operation of moving the slider to separate the stringers, that is to say, in the direction of the arrow 31, Fig. 3, the pull 15 will ride up on the spring finger 27, and depress this finger adjacent the pivot pin 24, causing the cross head to be moved into raised position, thus disengaging the pins 19 and 20 from the links or scoops. When the slider is at rest, the lock element will at all times assume a locked position, thus retaining the stringers against accidental separation.

The automatic lock element of the slider may also be described as a lever having a long flexible end arranged upon the slider wall, and a short rigid end terminating in a cross head disposed beyond the end of the slider wall. The flexible end has sufficient spring properties to maintain the cross head end of the lever or the projections thereof in operative position, while at the same time, presenting a bowed portion adjacent the pivot of the lever adapted to be depressed by the pull in throwing or swinging the cross head end of the lever into its inoperative position.

As above stated, the cross head of the lock element comprises more or less of an extension to the top wall of the slider, and thus might be said to comprise a pivoted or swinging wall portion. This structural arrangement, in addition to providing a simple automatic lock slider structure also produces a lock slider which will be free

from jamming, particularly in that the lock element is readily accessible externally of and beyond the limits of the slider body, contrary in this respect to lock elements which are housed within the slider body and inaccessible to the user in the event that the same becomes jammed for any reason whatever.

Furthermore, the simplicity of the construction as a whole simplifies the assemblage of the parts, in that the spring finger 27 can be coupled with the cross head body proper, and then the complete unit inserted into the aperture 16, after which the pivot pin 24 can be placed in position.

Having fully described my invention, what I claim as new and desire to secure by Letters Patent is:

1. A lock slider for separable fastener stringers, comprising a channelled slider body having spaced walls contracting at the narrow end of said body, an elongated loop on one wall of said body, a lock member of substantially T-shaped formation, the cross head of said member being arranged beyond the limits of said wall of the slider, the leg of said member extending into an aperture in the loop of said slider wall, means for pivoting the leg of said member to said loop, a spring finger extending from the leg of said member longitudinally of and beneath said loop, link engaging projections on the cross head of said member for retaining the slider against movement longitudinally of fastener stringers, and said spring finger normally supporting the projections of the lock member in operative position.

2. A lock slider for separable fastener stringers, comprising a channelled slider body having spaced walls contracting at the narrow end of said body, an elongated loop on one wall of said body, a lock member of substantially T-shaped formation, the cross head of said member being arranged beyond the limits of said wall of the slider, the leg of said member extending into an aperture in the loop of said slider wall, means for pivoting the leg of said member to said loop, a spring finger extending from the leg of said member longitudinally of and beneath said loop, link engaging projections on the cross head of said member for retaining the slider against movement longitudinally of fastener stringers, said spring finger normally supporting the projections of the lock member in operative position, and means movable longitudinally of the loop of said slider to engage the spring finger in raising the cross head to move the projections thereof out of engagement with the links of the stringers.

3. The combination with a slider of separable fastener stringers having wide and contracted end portions, of an automatic lock element, means pivotally supporting said element to the contracted end of the slider, said element having a part arranged beyond the limits of the slider body, said part having a lock pin for engaging the links of a fastener stringer, and a spring finger on said element operatively engaging the slider body to tensionally support the lock element in operative position.

4. The combination with a slider of separable fastener stringers having wide and contracted end portions, of an automatic lock element, means pivotally supporting said element to the contracted end of the slider, said element having a part arranged beyond the limits of the slider body, said part having a lock pin for engaging the links of a fastener stringer, a spring finger on

said element operatively engaging the slider body to tensionally support the lock element in operative position, and means movable longitudinally of the slider body and operatively engaging said spring finger to move the lock element into inoperative position.

5. In sliders for separable fastener stringers comprising a slider body having spaced channelled walls contracted at one end portion of the body, the combination with one wall of the slider body, of a member forming an extension to one wall of the slider at the contracted end thereof, means centrally of said member and extending onto said wall for pivotally supporting the member in connection with said wall, said member having a projecting lock part on the inner surface thereof, and tensional means normally supporting said member with the lock part thereof within the path of the channel portion of said wall of the slider.

6. In sliders for separable fastener stringers comprising a slider body having spaced channelled walls contracted at one end portion of the body, the combination with one wall of the slider body, of a member forming an extension to one wall of the slider at the contracted end thereof, means centrally of said member and extending onto said wall for pivotally supporting the member in connection with said wall, said member having a projecting lock part on the inner surface thereof, tensional means normally supporting said member with the lock part thereof within the path of the channel portion of said wall of the slider, said last named means comprising a long spring finger arranged longitudinally of and engaging said wall of the slider, and means movable longitudinally of the wall of the slider and engaging said finger to raise the lock part out of the path of the channel of said slider wall.

7. The combination with a slider having wide and contracted end portions, of an automatic lock element, said element comprising a lever like member pivoted to the slider adjacent the contracted end thereof, one short end of the lever being rigid and extending beyond the limits of the contracted end of the slider, said end having a projecting part on the under surface thereof, and the other end of said lever being long and flexible and extending onto and engaging the body portion of the slider adjacent the wide end portion thereof.

8. The combination with a slider having wide and contracted end portions, of an automatic lock element, said element comprising a lever like member pivoted to the slider adjacent the contracted end thereof, one short end of the lever being rigid and substantially of T-formation to provide an outer cross head end substantially equal in width to the width of the contracted end of the slider, said cross head having on the under surface thereof a projecting lock part, and the other end of the lever being in the form of an elongated spring finger extending onto and engaging the body portion of the slider.

9. In sliders for separable fastener stringers, a channelled slider body defined by spaced walls having narrow and wide end portions, a supplemental wall part at and extending beyond the narrow end of one wall of said body, means movably supporting the supplemental wall on said wall of the slider body, means for supporting the supplemental wall normally in approximate alignment with said wall of the slider body, a projecting lock element on the supplemental wall extending in the direction of and forming a

blocking element in front of the channel of the slider body to engage at least one of the stringers in retaining the slider body against movement thereon, and means movably supported on the slider body for moving the supplemental wall into raised position in the movement of said lock element into inoperative position.

10. The combination with a channelled slider body having spaced walls, of a supplemental wall part for one wall of said body and arranged beyond the limits of said wall and in substantial alignment therewith, means movably supporting the supplemental wall part upon said wall of the body whereby the supplemental wall may be raised and lowered with respect to said wall, and said supplemental wall having a lock element projecting from the lower surface thereof in the direction of and adapted to block the channel portion of the slider in spaced relation to said wall thereof.

11. The combination with a channelled slider body having spaced walls, of a supplemental wall part for one wall of said body and arranged beyond the limits of said wall and in substantial alignment therewith, means movably supporting

5 the supplemental wall part upon said wall of the body whereby the supplemental wall may be raised and lowered with respect to said wall, said supplemental wall having a lock element projecting from the lower surface thereof in the direction of and adapted to block the channel portion of the slider in spaced relation to said wall thereof, said supplemental wall part having yieldable means extending onto said wall of the slider, and means movably supported on said wall of the slider operatively engaging said yieldable means for moving the supplemental wall part and its lock element into inoperative position.

12. An automatic locking device for sliders of separable fasteners of the class described, said device comprising a bar having a transverse aperture to form a pivotal support for said bar, one end of the bar having a wide cross head offset with respect to one surface of the bar, a projecting lock element on said cross head, an elongated spring finger at the other end of said bar, and means for keying and securing the spring finger to the bar adjacent the aperture therein.
